COMBINED SHOE HORN AND KEY HOLDER

Thomas K. Tsutsui, 16824A Denker Ave.,
Gardena, Calif. 90247

Filed Aug. 12, 1970, Ser. No. 24,457

Term of patent 14 years

U.S. Cl. D86—10 Int. Cl. D28—99

FIG. 1 is a top plan view of a combined shoe horn and key holder showing my new design;

FIG. 2 is a right end view thereof;

FIG. 3 is a left end view thereof;

FIG. 4 is a bottom view thereof;

FIG. 5 is a top plan view of a modification of the design of FIG. 1;

FIG. 6 is a right end view thereof;

FIG. 7 is a left end view thereof; and

FIG. 8 is a bottom view thereof.

I claim:

The ornamental design for a combined shoe horn and key holder, as shown and described.
